UNITED STATES PATENT OFFICE.

ROBERT W. STROUT, OF SALEM, MASSACHUSETTS, ASSIGNOR TO VAUGHN MACHINE COMPANY, OF BOSTON, MASSACHUSETTS, A CORPORATION OF WEST VIRGINIA.

SHAVING-MACHINE.

SPECIFICATION forming part of Letters Patent No. 767,452, dated August 16, 1904.

Application filed April 2, 1904. Serial No. 201,270. (No model.)

To all whom it may concern:

Be it known that I, ROBERT W. STROUT, a citizen of the United States, residing in Salem, in the county of Essex and State of Massachusetts, have invented an Improvement in Shaving-Machines, of which the following description, in connection with the accompanying drawings, is a specification, like characters on the drawings representing like parts.

10 This invention relates to a machine for treating hides, skins, and leather, and is especially designed and adapted to be used for shaving skins.

15 In machines of the class described the skin is shaved by means of a bladed cylinder or roll which is revolved at a substantially high rate of speed.

20 The present invention has for one of its objects to provide a machine of the class described with which the imperfections in the skin caused by the chattering of the rapidly-revolving bladed cylinder or roll may be avoided, or at least reduced to a minimum. To this end the bladed cylinder is journaled 25 in the sides of a box-like frame, which is cast in one piece, is of rigid construction, and firmly braced.

Another feature of the present invention consists in providing a machine in which the 30 operating parts are reduced in number, and for this purpose the bladed roll or cylinder and the rotatable grinder are driven from the same shaft, which may be the main shaft of the machine.

35 The invention further has for its object to provide for simultaneously stopping rotation and travel of the grinding-wheel without stopping rotation of the bladed cylinder or roll, thereby economizing in the power employed 40 to operate the machine and diminishing the wear and tear upon the grinding-wheel, its operating parts, and the bladed cylinder or roll. Provision is made for adjusting the grinder with relation to the bladed cylinder 45 or roll.

These and other features of this invention will be pointed out in the claims at the end of this specification.

Figure 1 is a side elevation with parts broken away of a machine embodying this invention; 50 Fig. 2, a rear elevation of the machine shown in Fig. 1 looking toward the right; Fig. 3, a vertical section on the line 3 3, Fig. 2; Fig. 4, a detail in plan and section, on an enlarged scale, to be referred to; Fig. 5, a vertical section on the line 5 5, Fig. 2; Fig. 6, a detail in elevation, on an enlarged scale, to be referred to; Figs. 7 and 8, sectional details, on an enlarged scale, to be referred to; and Figs. 9 and 10, details to be referred to. 60

In the machine herein shown as embodying this invention the hollow box-like frame or casing is preferably cast in one piece and comprises side walls *a b* and end walls *c d*, connecting said side walls and having a cross-piece or top wall *e* connecting the sides *a b* near their upper ends and extended from the rear wall *c* toward the front wall *d* to leave an opening *f*, (see Fig. 5,) which is substantially closed by a movable top *g*, fitted to 70 slide on the side walls *a b* and provided with a detachable hood or bonnet *h*, having an opening *i*, which is normally closed by a cover *j* on the outer side of the said hood or bonnet.

The side walls *a b* are provided with beveled upper edges *k*, (see Figs. 2 and 7,) which are embraced by correspondingly-beveled side flanges *l*, depending from the movable top *g*. The side walls *a b* are extended upward beyond the end wall *c* to leave a space between 80 the top *g* and the cross-piece *e*, in which is located a rack-bar *n*, secured to the cross-piece *e* and engaged by a gear or pinion *o*, fast on a vertical shaft *p*, extended up into a hollow upright or standard *q*, attached to the top *g*, 85 and provided with an enlargement at its upper end to form a chamber *r*, provided with a removable cover *s* and in which is located a worm-gear *t*, fast on the spindle or shaft *p* and engaged by a worm *w* on a horizontally-extended shaft 10, supported in a hollow arm or boss 12, extended horizontally from the hollow standard *q*, the said worm-shaft being provided with a hand-wheel 13, by turning which rotation may be imparted to the vertical shaft 90 *p* and its gear *o*, which latter engages the fixed 95

rack-bar n , and thereby causes the sliding top g to be moved forward or backward, so as to engage a grinding wheel or disk 15 with a rotatable bladed or cutting cylinder 16. The cutting-cylinder 16 is journaled in fixed bearings carried by the side walls a b at their front upper end, and the grinding-wheel 15 is mounted to slide on a shaft 17, (see Fig. 7,) which is square or other than round in cross-section intermediate of its journals 18, which latter are supported in boxes 19, attached to the movable top g , one of said journals having fast to it a pulley 20, (see Figs. 1, 2, and 7,) which is connected by a cross-belt 21 (indicated by dotted lines, Fig. 1) with a pulley 22, normally loose on a shaft 23, having fast on it a pulley 24, one at each side of the machine. (See Fig. 2.) The pulleys 24 are connected by belts 25 with the pulleys 26 on the ends of the bladed cylinder 16. It will thus be seen that the grinding-wheel 15 and cutting-cylinder 16 are driven from the same shaft 23, which is provided with fast or loose pulleys x y .

25 The grinding-wheel 15 is movable longitudinally on the shaft 17 by means of a forked lever 28, (see Fig. 7,) the said lever having its hub 29 mounted to move longitudinally on a sleeve 30, fitted over a shaft 31, provided with 30 helical grooves 32 33, extended in opposite directions and into which projects a fork or curved piece 34, (see Figs 7 and 9,) having a pin or stud 134, carried by the under side of the hub 29 and extended through a longitudinal slot 35 in the under side of the sleeve 30, which constitutes a pivot for the lever 28, and, as shown in Fig. 7, is mounted to turn on the journal-bearings 37 for the shaft 31. The sleeve 30 acts as a guard or cover for the 35 shaft 31 and prevents the grooves thereof from becoming filled up with emery and metallic dust, which would render the machine inefficient and in time inoperative.

40 The shaft 31 may be rotated, as herein shown, by means of a bevel-pinion 40, fast on it and in mesh with a like pinion 41, fast on an inclined shaft 42, supported in suitable bearings 43 44, attached to the side a of the casing or hollow frame, the shaft 42 having at its lower end a 45 worm or spiral gear 45, which meshes with a worm 46, (see dotted lines, Figs. 1 and 4,) fast on a shaft 47, supported in bearings in the sides a b . The shaft 47 beyond the side b of the hollow casing has loose on it a pulley 49, (see 50 Figs. 2, 4, and 5,) adapted to be rendered fast thereon by a clutch of any suitable construction, one member, 50, of which is attached to the hub of the pulley 49 and the other member, 51, of which is keyed to the shaft 47 and is 55 adapted to be moved into engagement with the member 50 by a spring 52, supported by the hollow frame and engaging a lever 53, which is connected with the clutch member 51 in the usual manner, the lever 53 being pivoted to a 60 bracket 54, attached to the side b . The lever

53 is provided with a tailpiece or arm 55, with which coöperates a cam 56 on a rock-shaft 57, (see Figs. 3, 4, and 6,) supported in suitable bearings attached to the side b and provided with a crank arm or handle 58. The cam 56 70 acts to turn the lever 53 so as to disengage the clutch member 51 from the member 50 against the action of the spring 52, and thereby render the pulley 49 loose on its shaft 47, consequently stopping rotation of the grooved shaft 75 31 and travel of the forked lever 28. The rock-shaft 57 is designed to simultaneously control the rotation of the shaft 17, and for this purpose the rock-shaft 57 is provided with a second cam 60, which may be made, as herein 80 shown, by cutting away a section or portion of the shaft, (see Fig. 4,) which cam coöperates with a rod 61, sliding through the side b of the frame and attached to a clutch-lever 62, which is forked to engage studs or pins 63 on the opposite sides of a collar 64, mounted on the main shaft 23 to slide thereon.

The shaft 23 is made hollow at its end (see Fig. 8) to receive a pin or rod 65, which at its inner end has extended through it and a slot 165 in the shaft 23 a key 66, which engages the collar 64. The pin or rod 65 has mounted on it at its outer end a metal disk 67 and a fiber washer 68, which are adapted to engage the hub 69 of the pulley 22, the washer 68 and 95 disk 67 being retained on the rod 65 by nuts 70.

The pulley 22 is normally loose on the shaft 23, and, as shown in Fig. 8, the said shaft is provided with a sleeve 71, upon which the pulley 22 is mounted, the pulley 24 being rendered fast to the shaft 23 by a key 73 or in any other suitable manner. The pulley 22 is provided with an inclined peripheral flange 74, which coöperates with the inclined under surface 75 of the rim of the pulley 24, and when the inclined flange 74 is brought into engagement with the inclined surface 75 of the rim of the pulley 24 the normally loose pulley 22 is rendered fast to the pulley 24, which latter is fast on the shaft 23. The pulley 22 100 is rendered fast to the pulley 24 by movement of the clutch-lever 62 in the direction indicated by the arrow 77 in Figs. 2 and 8, which is effected by the full portion of the cam 60 engaging the rod 61, as shown in Fig. 110 6, which takes place, as herein shown, when the cam 56 is withdrawn from the lever 53, and the latter is turned by the spring 52 to clutch the pulley 49 onto the shaft 47. In other words, in the present instance the cams 115 56 60 are arranged on the rock-shaft 57 so as to act reversely—that is, when the cam 56 is not acting on the lever 53 the cam 60 is acting on the rod 61, and vice versa. The normally loose pulley 22 may be disengaged from 120 the fast pulley, as herein shown, by helical springs 80, inserted in pockets 81 in the hub 69 of the pulley 22, said springs encircling pins or rods 82, provided with heads 83, which extend through the end walls of the pockets 125 130

and engage the hub of the pulley 24, as shown in Fig. 8.

The rock-shaft 57 is supported in suitable bearings 84, attached to the side *b* of the box-frame, and its handle 58 may be located at its front end, so as to be accessible to the operator from the front of the machine.

It will thus be seen that the operator through the handle 58 has control of the grinding-wheel 15, so that by moving the said handle from its upright position (shown in Fig. 3) into a position which may be substantially diametrically opposite the rotation and the traverse of the grinding-wheel may be stopped without interrupting the rotation of the cutting cylinder or roll 16, which is desirable in this class of machines, as it enables the grinder to be stopped at any point of its traverse, thereby economizing in the power employed to operate the machine, and the wear upon the blades of the cutting-cylinder and also upon the grinder may be diminished by turning the feed-wheel 13 so as to move the grinding-wheel backward and out of contact with the cutting-cylinder. The grinder can be again set in motion to travel lengthwise of the cylinder by the operator moving the handle 58 into the position shown in Fig. 8.

The box-like frame has cast integral with it an extension 90, upon which are erected arms 91 92, to which are pivoted levers 93 94, which are connected by cross pieces or bars 95 96. (See Fig. 4.) The cross-piece 95 has pivotally secured to it at its center a yoke comprising a bar 97 and upright arms 98, in which latter is journaled the bed-roll 99 of any suitable or usual construction, the bar 97 being mounted to turn in a substantially horizontal plane to adjust the bed-roll in parallelism with the knife-cylinder. This adjustment may be effected by the screws 100, carried by the arms 101, attached to the cross-bar 95, said screws engaging the cross-bar 97 of the yoke on opposite sides of its pivot 102.

The levers 93 94 may be turned on their pivots to move the bed-roll toward the knife-cylinder when it is desired to shave a hide or skin placed over said bed-roll by a foot-treadle 103, having an arm carrying a screw 104, which engages the rear side of the cross-bar 96, and said bed-roll may be returned to its normal position away from the knife-cylinder 16 by a spring 105, encircling a rod 106 within a tube or cylinder 107, which is attached to a cross-bar 108, connecting the uprights 91 92. The cylinder 107 is closed at its outer end by a threaded plug or cap 109, against which bears the end of the spring 105, the other end of which bears against a washer or collar 110, fast on the rod 106, which extends loosely through the cap or plug 109 and through the bar 108 and is screw-threaded beyond the said bar and engaged by a thumb-nut 112, which co-operates with the cross-bar 108 and constitutes a stop to limit the forward movement

of the bed-roll 99 toward the knife-cylinder 16. When the bed-roll 99 is in its forward position, (represented in Figs. 1 and 5,) the spring 105 is compressed, and when the pressure of the foot is taken off from the treadle 103 the said spring acting against the collar 110 effects movement of the bed-roll away from the knife-cylinder.

It is to be observed that the spring 105 is located in a closed cylinder and is protected from dirt, &c., and is thereby kept in good working condition and is prevented from becoming inoperative.

By reference to Fig. 5 it will be seen that as the sliding top *g* is moved to adjust the grinding-wheel with relation to the knife-cylinder it carries with it the shaft 17, which causes the forked lever and its sleeve 30 to turn, thereby effecting the tension on the cross-belt 21, and when the grinding-wheel 15 is moved away from the knife-cylinder the cross-belt is slackened. The slack in the cross-belt is taken up by an idler-pulley 120, carried by a crank or arm 121, fast on a rock-shaft 122, which is supported in bearings 123, attached to the end wall *c* of the box-like frame, and is restrained from longitudinal movement by the collars 124 on said shaft. The rock-shaft 122 is turned in the proper direction to keep the pulley 120 in engagement with the cross-belt 21, and thereby automatically take up the slack in said belt, by a helical spring 125, encircling the rock-shaft and having one end fastened to a bearing 123 and the other end to a collar 126, fast on said rock-shaft.

By reference to the drawings, and especially Fig. 5, it will be seen that the box-like frame cast in one piece affords a firm and solid support for the knife-cylinder 16, which is thereby enabled to be driven at a substantially high speed with the least possible chattering or vibration, thus reducing to a minimum the imperfections in the skin due from this source.

I claim—

1. In a machine of the class described, in combination, a box-frame comprising the sides *a*, *b*, ends *c*, *d*, and cross-bar *e* extended from the end *c* but partially toward the end *d* to leave an opening *f*, a movable top dovetailed onto the sides *a*, *b*, and provided with a bonnet, a rack-bar affixed to the cross-bar *e*, a pinion in mesh with said rack-bar, an upright shaft on which said pinion is mounted, a hollow standard erected upon said movable top and provided with an enlargement at its upper end forming a chamber, a worm-gear fast on said upright shaft within said chamber, a shaft extended into said chamber and provided with a worm in mesh with said worm-gear, a rotatable cutting-cylinder supported by the sides *a*, *b*, a grinding-wheel within said box-frame co-operating with said cutting-cylinder, a shaft upon which said grinding-wheel is mounted to revolve therewith and to move lon-

5 longitudinally thereon, a shaft located below said grinding-wheel shaft and provided with helical grooves extended in opposite directions, a lever loose on said grooved shaft and engaging said grinding-wheel to effect movement of the latter on its shaft, a stud or pin carried by said lever and having a fork extended into a groove of said grooved shaft, mechanism to effect rotation of said grinder-shaft, mechanism to effect rotation of said grooved shaft, means to simultaneously control the rotation of said grinder-shaft and said grooved shaft, a bed-roll coöperating with said cutting-cylinder and movable toward and from the same, 15 and means to support said bed-roll, substantially as described.

2. In a machine of the class described, in combination, a rotatable cutting cylinder or roll, a grinding-wheel coöperating therewith, 20 means to rotate said grinding-wheel, means to effect bodily movement of said grinding-wheel longitudinally of said cutting-cylinder, and mechanism for simultaneously controlling the rotation and longitudinal movement of said 25 grinding-wheel, without effecting the rotation of said cutting-cylinder, substantially as described.

3. In a machine of the class described, in combination, a box-like frame provided with 30 a movable top having a bonnet or hood attached thereto, and mechanism carried by said movable top for effecting movement of the latter and its attached bonnet, substantially as described.

35 4. In a machine of the class described, in combination, a box-like frame provided with a movable top having a bonnet or hood attached thereto, a rack-bar secured to said frame, and an upright shaft carried by said movable top 40 and provided with a pinion in mesh with said rack-bar, whereby rotation of said shaft effects movement of said top, substantially as described.

5. In a machine of the class described, in combination, a rotatable grinding wheel or 45 disk, a shaft upon which said wheel is mounted to revolve therewith and to move longitudinally thereon, a rotatable shaft to effect longitudinal movement of said grinding-wheel 50 on its shaft, mechanisms for rotating said shafts, cams to control said mechanisms, and a rock-shaft to which said cams are attached, substantially as described.

6. In a machine of the class described, in combination, a rotatable grinding wheel or 55 disk, a shaft upon which said wheel is mounted to revolve therewith and to move longitudinally thereon, a rotatable shaft to effect longitudinal movement of said grinding-wheel on 60 its shaft, mechanisms for rotating said shafts, and means to simultaneously control the operation of said mechanisms, substantially as described.

7. In a machine of the class described, in 65 combination, a grinding-wheel, a shaft on

which said wheel is mounted to revolve therewith and to move longitudinally thereon, a rotatable grooved shaft, means for connecting said grooved shaft with said grinding-wheel, a driving-shaft for said grooved shaft, 70 mechanism connecting said driving-shaft with said grooved shaft, a pulley loosely mounted on said driving-shaft, a clutch to render said pulley fast on said driving-shaft, and means to operate said clutch, substantially as described. 75

8. In a machine of the class described, in combination, a grinding-wheel, a shaft on which said wheel is mounted to revolve therewith and to move longitudinally thereon, a 80 rotatable grooved shaft, a sleeve fitted over said grooved shaft and having a longitudinally-extended slot in its under side, a stud or pin extended through said slot and engaging said grooved shaft, a device connected with said 85 grinding-wheel and mounted on said sleeve, said stud or pin being secured to said device to effect longitudinal movement of the said grinding-wheel by rotation of said grooved shaft, and means to effect rotation of said 90 grinding-wheel shaft and said grooved shaft, substantially as described.

9. In a machine of the class described, in combination, a bladed cylinder or roll, a rotatable grinder coöperating therewith and 95 movable toward and from said bladed cylinder, a driving-shaft, means for connecting said bladed cylinder with said driving-shaft, independent means for connecting said rotatable grinder with said driving-shaft, and 100 means to control rotation of said grinder independent of the said bladed cylinder substantially as described.

10. In a machine of the class described, in combination, a supporting-frame, a rotatable 105 bladed cylinder or roll journaled in said frame, a rotatable grinder coöperating with said cylinder or roll, a shaft upon which said grinder is mounted, bearings for said shaft, means extended across the said frame to connect the 110 said bearings together, said means being movable on said frame toward and away from said cylinder or roll, and mechanism to effect movement of said means, substantially as described.

11. In a machine of the class described, in combination, a bed-roll, a pivoted support for 115 said bed-roll, means to move said support in one direction, a spring to move said support in an opposite direction, a cylinder in which said spring is located, a rod extended through 120 said cylinder and engaged by said spring to move it in one direction, said rod coöperating with said support to move the latter under the influence of the spring, and means on said rod to limit the movement of the pivoted support 125 in one direction, substantially as described.

12. In a machine of the class described, in combination, a box-like frame comprising sides and ends connecting said sides and integral therewith, a rotatable bladed cylinder or 130

roll journaled in said frame, a driving-shaft for said roll or cylinder journaled in said frame, means to connect said cylinder or roll with said shaft, a movable top for said frame 5 extended across the same and slidable thereon in a direction substantially at right angles to the axis of said cylinder or roll, a shaft supported by said movable top substantially parallel with the axis of said cylinder or roll, a 10 grinder mounted on the shaft carried by said movable top to move longitudinally thereon, means to rotate said grinder, and means to effect movement of said grinder longitudinally on its shaft substantially as described. 15 13. In a machine of the class described, in combination, a one-piece frame, a rotatable bladed cylinder or roll journaled in said frame, a top for said frame extended across the same and slidable thereon in a direction substantially 20 at right angles to the axis of said cylinder or roll, a grinder carried by said top toward and from the cylinder or roll and movable in the direction of the axis of said cylinder and means to move said top, substantially as described.

the direction of the axis of said cylinder and means to move said top, substantially as described. 25

14. In a machine of the class described, in combination, a box-like frame, a rotatable bladed cylinder or roll journaled in said frame, a top for said frame extended across the same and slidable thereon in a direction substantially 30 at right angles to the axis of said cylinder or roll, a grinder carried by said top toward and from the cylinder or roll and movable in the direction of the axis of said cylinder and means to move said top, substantially as described. 35

In testimony whereof I have signed my name to this specification in the presence of two subscribing witnesses.

ROBERT W. STROUT.
